UNITED STATES PATENT OFFICE.

GEORGE F. MILLIKEN, OF BOSTON, MASSACHUSETTS, ASSIGNOR TO THE GAME-WELL AUXILIARY FIRE ALARM COMPANY, OF SAME PLACE.

ELECTRIC SIGNALING APPARATUS.

SPECIFICATION forming part of Letters Patent No. 394,784, dated December 18, 1888.

Application filed June 21, 1888. Serial No. 277,777. (No model.)

To all whom it may concern:

Be it known that I, GEORGE F. MILLIKEN, of Boston, in the county of Suffolk and State of Massachusetts, have invented certain Improvements in Electric Signaling Apparatus, 5 of which the following is a specification.

This invention relates to electric alarms or signals, and more especially to such as operate with a continuous ring brought about by the automatic magnetization and demagnetization of the signal-actuating electro-magnet. Its main object is to provide a return or responsive signal for any main or auxiliary municipal system of electrical alarms or calls, 15 whereby the due operation of the distant alarm-receiving apparatus may be caused to automatically indicate or announce itself at the sending-station, so that it shall unquestionably be known that the apparatus has 20 fully and efficiently performed its office.

To this end it consists in the combination, with such a system, of an electro-magnet in a normally-open electric circuit, the same being provided with an armature normally retracted 25 to a position intermediate between its extreme front and rear limits, so that when the said armature is at rest the circuit which passes through its magnet-helices, a battery, the armature itself, and through vibrating contacts 30 at the rear limit shall remain open.

It consists, moreover, in combining such systems, when so provided, with suitable means for setting up initial vibrations in the said armature, which, rebounding, passes its 35 point of rest, and, making contact with the circuit-closing point of its rear limit, closes the circuit of its actuating-magnet through the same, and thereupon is attracted, and continues to vibrate until the battery is exhausted or until positively stopped. The preferable way of setting the armature initially in motion is to provide that the same electro-magnet shall be included also in a second circuit, which shall also be normally open, but 40 which is provided at any point or points with a suitable circuit-closer, which, when operated, causes the magnet to become energized and thereupon to attract its armature. When the circuit is again opened, the armature will 45 fall back beyond its normal position, and, reaching its back stop, will allow the magnet

to become again energized, but this time in the first circuit, and with the result, as already stated, of setting up continuous vibration, though the starting-circuit be now maintained 55 open. It is immaterial whether the same battery be, as well as the electro-magnet, common to both circuits or whether each be provided with an individual battery.

It will be seen that the invention is based 60 upon a peculiar arrangement of mechanism, which, not new in itself, is here for the first time rendered available as a response or return signal in combination with a system of fire or other alarms—viz., that an armature 65 forming part of an electric circuit, including its magnet, a battery, and vibrating points, and normally occupying an intermediate position or point of rest in advance of its rear stop, and thus maintaining its circuit open, 70 will, when once set in vibration, either electrically or otherwise, continue to vibrate upon its back stop, its magnet being alternately magnetized and demagnetized. The electro-magnet may, when used as a return-signal, 75 operate simply as a “buzzer,” or the armature may, if desired, be furnished with a bell-hammer and arranged to strike a bell.

The drawing, which illustrates and forms a 80 part of this specification, shows an electrical system of fire-alarms in which my invention is incorporated as a response-signal.

In the figure, *m* is the signal electro-magnet, *a* its armature, and *B* its vitalizing-battery. 85

The drawing shows my invention embodied in a system of auxiliary fire-alarm substantially identical with that for which Letters Patent No. 377,083 were granted to myself and H. B. Lytle, jointly, January 31, 1888. 90 In this system the street-box of any municipal fire-alarm included in the regular fire-alarm circuit 5 operates the said circuit by means of a suitable break or signal wheel, *x*, and a contact-spring, 12, and when in operation breaks and makes the said circuit, which includes a battery, *B*², and thus is adapted to transmit signals to the fire-station. (Not shown.) This box is controlled by an electro-magnet, 6, in an auxiliary alarm-sending circuit, *T*, which is led through one or more auxiliary or local alarm-sending stations, *C*. At 95 100

any of these stations (I have for greater clearness here shown but one) the auxiliary circuit T may be closed, and the magnet 6 in the box then acts to trip the mechanism and 5 to allow the rotation of the signal-wheel. The auxiliary alarm-circuit T is at all times closed on a small battery, B', which, however, does not furnish a current sufficiently strong to energize the releasing electro-magnet 6 in 10 the box R. The normal route of this circuit may be thus traced: from battery B' by wire 4 to electro-magnet 6; thence by wire 7, contact-point 8, circuit-breaking lever 9, wire w to switch-pivot u at home station C, switch s, 15 switch-button 1, and by wire o to the other pole of the small battery. By suitable appliances, forming no part of this invention, the continuity of this circuit can, by the aid of the small battery B', be at any time tested. 20 The alarm-sending apparatus at station C consists of a circuit-changing switch, s, operated by a chain, rod, or cord, t, and ring r, or equivalent starting device. This switch connects with three buttons, 1, 2, and 3, being 25 normally, as shown, upon 1, and when the alarm is sent, which is effected by pulling the ring r, it passes from 1 to 3, making contact intermediately with 2. In this system the object of the electro-magnet m is to serve as 30 a return-signal, and to that end its terminal wires p and q are led, respectively, to the switch-studs 2 and 3. Switch-stud 2 is likewise united by wire y with one pole of battery B, which is so large that when introduced 35 into the alarm-circuit T the current flowing therein will be strong enough to energize the box-magnet 6 and trip the mechanism. It must be noted that the responsive signal-magnet m is provided with an armature, a, mounted on a retracting and supporting spring, b, and that this armature, when at rest, occupies an intermediate position between its front and back limits of motion, so that it is not normally in contact with the 40 back contact-spring, h, which, by wire f, is united to switch-stud 1. The armature a, through its bracket b, is also united by a wire with the pivot of switch s. The magnet m is, 45 by virtue of these connections, common to two circuits—viz., the auxiliary signal-circuit and a local shunt of the same—and the closing of the former circuit through the battery B and magnet, as described, followed by the opening thereof, transfers both battery and 50 magnet to the shunt-circuit, whereby a continuous alarm is maintained after the auxiliary circuit is opened.

It should now be stated that in the operation of the auxiliary fire-alarm it is desirable 55 that the sender of an alarm should in all cases receive a responsive signal, whereby he may know not only that the signal has reached the box, but also that the box has been set in motion and has in turn fulfilled its functions.

60 In the patent which I have hereinbefore cited such a device is shown; but my present invention is especially well adapted for this pur-

pose, and its function is, by virtue of a change in the main auxiliary circuit, effectuated by the motion of the box mechanism to furnish 70 the response-signal, which it does by acting as a buzzer.

Included in the circuit T, and inclosed within the box R, is a switch or circuit-breaker, 9, arranged to be acted upon by the arm 11, which is fastened by a sleeve or otherwise to the axis of the signal-wheel x. The arm 11 in passing round engages with the switch-lever 9, forcing it away from its contact 8, and thus opens the circuit T, and this operation it is which 80 actuates the responsive signal.

If an alarm is to be sent in from station C, the ring r is pulled down. When in transit it first makes contact with stud 2, the circuit of the large battery B is closed on the main 85 line through the box-starting magnet releasing the mechanism; but the buzzer-magnet m is not yet introduced. Continuing to pull the ring r downward, contact is next made with the lowest stud, 3, when the circuit of the battery B is still closed on the main line, as before, but now includes also the magnet m, which in consequence attracts its armature. As the box mechanism continues to rotate, the circuit-breaking switch 9 is operated, breaking 90 the main circuit T. The armature of the buzzer-magnet now falls back; but the force of its spring carries it back beyond its normal position into contact with the spring h. This short-circuits the battery B through the buzzer-magnet m and its armature and vibrating points, and vibrations are set up, which continue as long as the starting ring or hook is held down, maintaining the lever or switch on stud 3. The alarm-sender is almost instantly 100 informed, therefore, that his signal is received by the responding buzz of the magnet m and its armature, and may let go the ring at once.

It is obvious that my invention is especially well adapted for application to this and similar systems. I desire to point out that, though I have shown the controlling-circuit as being of considerable length, I do not restrict myself to any special length or form.

I do not claim as my invention a device in 115 which an electro-magnet in a normally-open circuit, including its armature and vibrating circuit-breaker operated thereby, is also common to a second and normally-closed circuit, by which it is normally energized, so that its 120 armature is normally attracted to its forward position and the vibratory circuit maintained inoperative as long as the closure of the second circuit is continued, this being old in the art. On the contrary, one of the principal advantages of my invention is, that it allows the controlling-circuit to be normally open, or, if desired for testing, to have but a small battery closed thereon, and thereby is extremely economical in maintenance, since the use of an 125 open-circuit main battery, with its consequent saving in battery material, is thus made possible.

For the purposes of this invention it is not

necessary in all cases that the circuit originally be absolutely open as a whole, the conditions being equally fulfilled if it be open so far as concerns the electro-magnet or the operating-battery.

5 I claim—

1. A municipal or other electric alarm system, comprising a main electric circuit, a main battery, and a response-signal magnet, both normally disconnected from the said circuit, and a key or switch adapted to be manually operated, and thereby to introduce successively the battery and magnet into the said main circuit, a normally-open shunt-circuit of the same battery, including the said magnet, and also its armature and back stop or vibratory contacts, all at the alarm-sending station, and a clock mechanism, an electro-magnet controlling and adapted when energized to release the same, and a circuit-breaking device actuated by the said mechanism, both electro-magnet and circuit-breaking device being included in the said main circuit, all at a second or alarm-receiving station, whereby the magnet of the response-signal at the home station may be constantly energized by the battery-current in the main circuit when the signal is sent, and intermittently energized and caused to give the response-signal, by inclusion together with its armature and vibratory points in the shunt-circuit upon the automatic operation of the distant circuit-breaker by means of the clock mechanism at the alarm-receiving station, substantially as hereinbefore described.
2. In an auxiliary fire-alarm-telegraph system, the combination, with a main circuit, a signal-transmitting device acting to introduce a battery into the said circuit, and an electro-magnet in a fire-alarm box at a distant station, said magnet being adapted when energized to trip the mechanism of said box, of a response or return signal comprising an electro-magnet introduced into the main circuit

45 by the act of sending the signal, a spring-armature and back contact therefor normally out of contact with one another, and a normally-open shunt-circuit of the main battery controlled by the said armature and back contact and including the said magnet, and 50 an automatic circuit-breaker in the main circuit operated by the box mechanism when tripped, and acting to break the said main circuit through the response-magnet, whereby the armature thereof is allowed to rebound 55 upon its back contact, and thereby to close the shunt-circuit and to give a vibratory signal, substantially as described.

3. A main electric circuit, a battery and an electro-magnet normally disconnected therefrom, and an armature for the said magnet, which armature when at rest is out of contact with its back stop, a normally-open shunt or local circuit through the said armature and its back stop or contact, and adapted when 60 closed to include also the electro-magnet and battery, a circuit-closing switch or key arranged to include the said battery and electro-magnet in the main circuit and to close the same, causing the magnet to be energized 65 and to attract its armature, and an independent and automatic circuit-breaker to open the said main circuit for the purpose of allowing the armature to rebound beyond its point of rest and to make contact with its back 70 stop and vibrate thereon, thus directing an intermittent or vibratory current through the shunt-circuit and electro-magnet and producing a continuous signal, substantially as hereinbefore described.

80 In testimony whereof I have signed my name to this specification, in the presence of two subscribing witnesses, this 16th day of June, 1888.

GEORGE F. MILLIKEN.
